CLAIM

The ornamental design for a display screen with animated graphical user interface for vehicle, as shown and described.

DESCRIPTION

FIG. 1 is a front view of a display screen with animated graphical user interface showing the first image in a sequence;

FIG. 2 is a front view thereof showing the second image in the sequence;

FIG. 3 is a front view thereof showing the third image in the sequence;

FIG. 4 is a front view thereof showing the fourth image in the sequence; and,

FIG. 5 is a front view thereof showing the fifth image in the sequence.

The outer-most broken-line perimeter illustrates a display screen and forms no part of the claimed design. The remaining broken lines illustrate portions of a graphical user interface and form no part of the claimed design.

The appearance of the display screen with animated graphical user interface sequentially transitions between images shown in FIGS. 1-5.

The subject matter in this patent includes a process or period in which an image changes into another image. This process or period in which one image transitions to another forms no part of the claimed design.

The process or period in which one image transitions to another forms no part of the claimed design.
